ADJUSTABLE DISPLAY SHELVING

Nils Herman Cederquist, Los Angeles, Calif.

Application March 5, 1938, Serial No. 194,085

7 Claims. (Cl. 211—128)

This invention relates to improvements in adjustable display shelving and to devices for adjustably mounting the shelves of display shelving on their supporting structures.

An object of the invention is to provide a simple, inexpensive, and durable device by which shelves or trays used for display purposes may be mounted on their supporting structures in such a manner as to enable them to be adjusted into whatever position is desired to properly display articles supported thereon.

In displaying articles of merchandise for sale it is frequently desirable to have the shelves or trays on which the articles are positioned inclined downwardly and forwardly toward the observer at various angles. The position of the tray or shelf that is desired frequently is dependent upon the nature of the article or articles displayed thereon. It also frequently occurs that within the same display cabinet or supporting structure it is desired to adjust the trays or shelves forwardly and backwardly and to cause the trays or shelves to assume various or non-uniform positions within the same supporting structure. The improved construction enables a multitude of adjustments so that the articles to be displayed may be most advantageously and tastefully arranged.

With the foregoing and other objects in view, which will be made manifest in the following detailed description and specifically pointed out in the appended claims, reference is had to the accompanying drawing for an illustrative embodiment of the invention, wherein:

Figure 1 is a view in front elevation of a display cabinet embodying the present invention;

Fig. 2 is a vertical section taken substantially upon the line 2—2 upon Figure 1 in the direction indicated;

Fig. 3 is a partial horizontal section through the left hand standard of the display cabinet shown in Figure 1 and through the adjacent end wall of the tray or shelf supported thereby, illustrating the mechanism employed that permits of the adjustment;

Fig. 4 is a sectional view taken substantially upon the line 4—4 upon Fig. 3 in the direction indicated; and

Fig. 5 is a view in perspective illustrating one of the plates forming a part of the present invention, together with its associated key.

Referring to the accompanying drawing wherein similar reference characters designate similar parts throughout, the invention may be embodied on any suitable structure having shelves or dis-

play trays supported between standards. I have illustrated the invention as having been applied to a display cabinet having standards 10 and 11, the opposed faces of which are horizontally grooved with a series of grooves indicated at 12.

Within these grooves are slidably disposed the horizontal fin portions 13 of keys generally designated at 14. These keys may be formed of sheet metal and at the ends of the fin portions they are provided with lugs 15 and 16, the metal 10 between these lugs being bent downwardly as indicated at 17 to form a bracing portion. The shelves or trays may be of any preferred construction and are indicated at 18.

The construction shown has a bottom and 15 upright ends, the ends being indicated at 19 and 20 on each tray. There may be forward walls provided on the trays in the form of plate glass sections 21, the ends of which are recessed in the inner faces of the end walls 19 and 20. The 20 outer faces of the end walls 19 and 20 are recessed or grooved with broad shallow grooves 22 and within these grooves there are disposed socket plates 23. Each socket plate is in the form of a flat rectangular section of sheet metal that fits 25 between the top and bottom of each groove 22. It has a central aperture 24 preferably countersunk which receives a fastening screw 25 which is driven therethrough into the end wall of the shelf or tray. Around the aperture 24 as a center 30 there are a plurality of pairs of circumferentially arranged slots constituting sockets, one pair of slots indicated at 26 and 27 is preferably arranged horizontally even with aperture 24. A second pair of slots indicated at 28 and 29, respectively, are radially arranged with respect to aperture 24, slot 28 being arranged above slot 26 and slot 29 being arranged below slot 27. A third pair of slots indicated at 30 and 31 are also radially arranged, slot 30 being above slot 28 and 40 slot 31 being below slot 29. These slots which form sockets are designed to receive the lugs 15 and 16 selectively, that is lugs 15 and 16 may be positioned either in slots 26 and 27 or slots 28 and 29 or slots 30 and 31. The number of pairs 45 of slots or sockets may be increased or decreased as occasion requires. Recesses 32 and 33 are bored into the end walls of the trays or shelves beneath the groups of slots so as to accommodate those portions of the lugs 15 and 16 that project 50 through the socket plates.

The operation and advantages of this construction are as follows: With the shelves or trays equipped at their ends with the socket plates and the supporting standards 10 and 11 55

provided with the keys and grooves it is possible to give each tray practically any desired position that will most advantageously display the articles positioned thereon. If it is desired to support 5 any or all of the shelves or trays in a horizontal position, the keys are positioned with their lugs 15 and 16 in the horizontal slots 26 and 27 and then the fin portions 13 are slidably entered into the grooves 12. By sliding the keys back and 10 forth in the grooves, the shelf may be given any forward or backward adjustment with respect to the supporting standards. When, however, it is desired to support any shelf or tray in an inclined position, the lugs 15 and 16 may be inserted either in socket slots 28 and 29 or 30 and 15 31, depending upon the nature of the inclination desired. In either inclined position, the tray may be adjusted forwardly or backwardly by sliding the keys in grooves 12.

20 It will be noted that in this construction that when the keys are in position in the grooves and socket slots that the trays are locked against rotating either in a clockwise or counter-clockwise direction, consequently it is immaterial whether 25 the center of gravity of any tray and the article positioned thereon is forwardly of or behind the center of the support which is through screws 25. Thus, no balancing of articles on the trays or shelves is necessary and the shelves cannot be 30 inadvertently or accidentally tipped to spill the articles displayed thereon. Rotational adjustment can only be accomplished by sliding the keys out of the ends of the grooves 12, then removing the keys from the socket slots and re-positioning the keys in another pair of socket 35 slots.

It will be appreciated that the present construction is very inexpensive, is highly durable, and may be easily and quickly applied to display 40 shelves and supporting standards therefor.

45 It will be understood that the present invention may be incorporated in the construction of the display shelves themselves. In other words, if the display shelves have metallic end walls, it is unnecessary to provide the slots 26 to 31, inclusive, in a separate plate applied thereto. Instead, these slots may be formed directly in the metallic end walls and accommodate the keys 13 equally well.

50 Various changes may be made in the details of construction without departing from the spirit or scope of the invention as defined by the appended claims.

I claim:

55 1. A fitting for adjustable display shelving comprising a plate attachable to a shelf or tray, said plate having a plurality of pairs of sockets radially arranged about a center, and a key having lugs selectively receivable in any pair of slots 60 and presenting a fin receivable in a groove of a supporting structure.

2. A fitting for adjustable display shelving

comprising a plate attachable to a shelf or tray, said plate having a plurality of pairs of sockets radially arranged about a center, and a key having lugs selectively receivable in any pair of slots 5 and presenting a fin receivable in a groove of a supporting structure, there being a bracing portion between the lugs on the key adapted to lie against the supporting structure.

3. Adjustable display shelving comprising a supporting structure presenting opposed walls, 10 there being substantially horizontal grooves in the walls, shelves disposed between the walls, there being a plurality of sockets in each end of each shelf, and keys selectively receivable in the sockets having portions receivable in the grooves 15 whereby the position of each shelf with respect to its keys may be varied and each shelf may be supported by its keys upon the walls.

4. Adjustable display shelving comprising a supporting structure presenting opposed walls, 20 there being substantially horizontal grooves in the walls, shelves disposed between the walls, there being a plurality of sockets in each end of each shelf, and keys selectively receivable in the sockets having portions receivable in the grooves 25 whereby the position of each shelf with respect to its keys may be varied and each shelf may be supported by its keys upon the walls anywhere along the length of their respective grooves.

5. Adjustable display shelving comprising a 30 supporting structure presenting opposed walls, there being substantially horizontal grooves in the walls, shelves disposed between the walls, there being a plurality of sockets in each end of each shelf, and keys selectively receivable in the 35 sockets having portions receivable in the grooves whereby the position of each shelf with respect to its keys may be varied and each shelf may be supported by its keys upon the walls, the arrangement being such that the ends of each shelf 40 largely conceal its respective keys when assembled.

6. Display shelving comprising a supporting structure presenting opposed walls which are horizontally grooved, shelves between the walls, 45 sockets on the ends of the shelves and keys having portions fitting in the grooves and fitting in the sockets disposed between the ends of the shelves and the walls whereby the shelves may be supported by the keys and adjusted along the 50 lengths of the grooves.

7. Display shelving comprising a supporting structure presenting opposed walls which are horizontally grooved, shelves between the walls, 55 sockets on the ends of the shelves and keys having portions fitting in the grooves and fitting in the sockets disposed between the ends of the shelves and the walls whereby the shelves may be supported by the keys and adjusted along the lengths of the grooves, the keys being largely 60 concealed by the ends of the shelves.
